UNITED STATES PATENT OFFICE

96,809

DESIGN FOR A SHOE OR SIMILAR ARTICLE

Marcel M. Braun, Chicago, Ill.

Application July 22, 1935, Serial No. 57,773

Term of patent 3½ years

To all whom it may concern:

Be it known that I, Marcel M. Braun, a citizen of the United States, residing in Chicago, in the county of Cook and State of Illinois, have invented a new, original, and ornamental Design for a Shoe or Similar Article, of which the following is a specification, reference being had to the accompanying drawing, forming part thereof.

I claim:

The ornamental design for a shoe or similar article as shown.

MARCEL M. BRAUN.
